UNITED STATES PATENT OFFICE.

WILLIAM HENRY SMEDLEY, OF STOKE-ON-TRENT, ENGLAND.

DISPLAY CARD, PRICE TICKET, AND THE LIKE.

Application filed February 23, 1927, Serial No. 170,292, and in Great Britain September 19, 1925.

This invention relates to improvements applicable in connection with display cards to be exhibited in shop windows or the like, price tickets for attachment to articles to be sold, calendars, cut-outs, or other articles where at present the means of support is the usual cardboard strut, or the only means of attachment is string or the like which is not capable of supporting the ticket at any desired angle. By the use of the improvements according to the invention, a display card or calendar or cut-out, as the case may be, can be supported at various angles of inclination without trouble, or a price ticket can be attached to the article to be sold with the ticket arranged at the best angle for viewing conveniently.

In accordance with the present invention, I employ in connection with the display card, price ticket or the like, a length of metal strip of suitable section covered with paper, cotton or the like to form a sheath, (the material of the covering being braided, if desired) and fastened securely thereto preferably by an adhesive pad. The length and cross section of the covered or braided strip are adjusted to the purpose for which it is intended and the article to which it is applied, and it may be furnished with a tag at one end and be flattened out at the other where it is attached to the display card, ticket or the like, so as to cause as little protuberance as possible. Where the strip takes the place of a cardboard strut, as for display cards, calendars or the like, which are of (relatively) considerable weight, it may be $\frac{3}{8}$ " or more in breadth, but for attaching a price ticket to an article such as a cup, it will preferably be a little thicker than string or twine.

The strip so formed is sufficiently flexible to bend into any desired shape or position, and yet sufficiently stiff without being springy to stop in the shape or position into which it has been bent.

The invention is illustrated by way of example in the accompanying drawings, in which:

Fig. 1 shows its employment as a supporting strut in connection with a display card, calendar or the like, a view from the rear being shown.

Fig. 2 is a side view corresponding to

Fig. 1, but with the strut actually in position supporting the article. 55

Fig. 3 is a rear view showing the application of the invention to a price ticket, Fig. 4 showing the ticket actually in use on the handle of the cup.

Fig. 5 is a cross-section on an enlarged scale of the strip shown in Fig. 1, the section being on the line A—A of that figure.

Referring to Fig. 5 of the drawings, the metal A which forms the core of the covered or braided strip is chosen according to the work which it has to perform. For most purposes lead will probably be preferable, but brass, copper, zinc or the like may be employed to give greater stiffness and strength, provided that they are sufficiently flexible to bend into the required position. The strip A may be rectangular, circular or other section as found most desirable. It is covered with a flexible material B of paper, cotton or the like, which may be braided, if desired, and which forms a sheath which helps to retain the metal strip in the position into which it may be bent. The braided or covered strip is preferably attached to the article (display card, price ticket or the like) by an adhesive pad C (Figs. 1 and 3.)

The stiffness yet flexibility of the attachment allows the display card to be tilted to various angles (Fig. 2) or the price ticket to be held in a desired position (Fig. 4) 85 in which it can easily be read.

As has been said above, the attachment of the covered or braided strip to the article is preferably by means of an adhesive pad at the back of the latter, as this is probably the simplest and cheapest method. Nevertheless, other forms of attachment may be used during the manufacture of the article.

I claim:—

A display device comprising a card and a flexible non-resilient support connected thereto, said support comprising a metallic core and a sheathing adhesively secured to said core, and said support being adapted to have one end portion bent over a third element to frictionally grip the same and to carry by its other end portion said card and to support the same in any position of adjustment. 100

WILLIAM HENRY SMEDLEY.
